(57) **CLAIM**

The ornamental design for a nozzle chest of a steam turbine, as shown and described.

DESCRIPTION

FIG. 1 is a front perspective view of a nozzle chest of a steam turbine showing our new design;

FIG. 2 is a front elevational view thereof;

FIG. 3 is a back elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken lines shown represent unclaimed subject matter and form no part of the claimed design.
